SUPPORT BASE FOR LETTER TRAYS

Christoph P. Meyer, 3860 Glencairn,
Indianapolis, Ind. 46226

Filed June 27, 1968, Ser. No. 12,520

Term of patent 14 years

Int. Cl. D19—02

U.S. Cl. D74—9

Fig. 1.

Fig. 3.

Fig. 2.

FIG. 1 is a perspective view of my holder, showing my new design.

FIG. 2 is a top plan view thereof.

FIG. 3 is a cross sectional view taken on line 3—3 of FIG. 2.

The broken line representation of letter trays in FIG. 1 are for purposes of illustration only.

I claim:

The ornamental design for a support base for letter trays, as shown and described.
